HIGH VOLTAGE RECTIFIER OR INVERTER

Joseph Slepian, Pittsburgh, Pa., assignor to Westinghouse Electric & Manufacturing Company, East Pittsburgh, Pa., a corporation of Pennsylvania

Application November 24, 1937, Serial No. 176,261

12 Claims. (Cl. 250—27.5)

My invention relates to electric discharge devices, and particularly to high voltage rectifiers or inverters.

An object of my invention is to provide a discharge device for heavy duty having reliable operation and freedom from backfires.

Other objects and advantages of the invention will be apparent from the following description and drawing, in which the single figure is a cross sectional view illustrating a preferred embodiment of my invention.

In particular my invention contemplates utilizing a blast of ionized vapor to establish the arc to the anode and likewise contemplates utilizing a blast of fresh un-ionized vapor to extinguish the arc and to insure that there are no backfires.

In the figure is disclosed a casing 10 of the metallic type having an anode 11 therein insulated from the casing by any suitable insulation such as 12 sealed to both the anode and the casing. This anode is preferably cooled by a medium such as the liquid 13 illustrated, which passes through the inlet 14 and the outlet 15. In the bottom portion of the casing is a liquid cathode 16 such as mercury. The interior of the casing has a gaseous atmosphere at preferably several atmospheres pressure, preferably by means of a gas such as argon, helium or hydrogen. I prefer to restrict the striking area on the liquid cathode exposed to the anode and for such restriction I prefer to utilize insulating means 17 having a funnel shaped throat or hollow portion 18 extending towards the liquid cathode surface and preferably extending below the surface thereof. The insulating means may also have an extended surface 19 to normally prevent the arc from striking other portions of the liquid cathode except for the bottom portion 20 in the throat 18.

In order to establish the arc, I utilize a make-alive 21 constructed of high resistance material such as boron carbide and having a portion immersed into the liquid mercury. The connection 22 extends through the liquid cathode and casing by means of any suitable insulation 23. This make-alive electrode 21 is more particularly described in Patent No. 2,069,283, issued February 2, 1937, to L. R. Ludwig and myself as joint inventors. The make-alive is so connected as described in this patent that a cathode spot is created on the mercury surface adjacent the make-alive at the beginning of the conductive portion of each cycle of alternating or pulsating current.

I prefer to have an extension 24 extending over the make-alive which is placed at one side of the throat 18 of the refractory insulating means 17

in order to protect the make-alive from the direct arc path from the anode to the exposed surface 20 of the liquid cathode and also for the purpose of further restricting the throat 18.

In operation a cathode spot is formed at the surface of the mercury cathode at 20 and the mercury boils vigorously, thus producing a strong blast of mercury vapor at several atmospheres pressure. This strong blast of mercury vapor will carry the arc which was struck to the make-alive up to the anode 11 and establish the breakdown of the tube. When it is desired that the tube stop operating, the current to the make-alive is cut off and when the current comes to zero, the boiling of the mercury at the surface 20 will carry a fresh blast of un-ionized vapor that extinguishes and prevents the reignition of the arc. Because of the fact that a strong blast of vapor is always travelling up in the throat, there will be no tendency for the arc to backfire against this blast.

My invention, accordingly, provides a very reliable structure for very heavy duty. It is apparent, however, that many modifications may be made in the preferred embodiment which I have disclosed without departing from the spirit of the invention, and, accordingly, I desire only such limitations on the following claims as are necessitated by the prior art.

I claim as my invention:

1. An electric discharge device comprising a casing having a mercury cathode, an anode, stationary funnel shaped insulating means at the surface of the mercury cathode having its wider-open end facing said anode and stationary means for igniting an arc at the surface of said mercury cathode within said funnel shaped insulating means.

2. An electric discharge device comprising a casing having a gaseous atmosphere of several atmospheres, a mercury cathode, an anode, funnel shaped insulating means at the surface of the mercury cathode and means for igniting an arc at the surface of said mercury cathode within said funnel shaped insulating means.

3. An electric discharge device comprising a casing having a mercury cathode, an anode, funnel shaped insulating means at the surface of the mercury cathode having its wider-open end facing said anode and means for creating a new cathode spot at the beginning of each conducting portion of the cycle of current within the funnel shaped portion of said insulating means.

4. An electric discharge device comprising a casing having a mercury cathode, an anode, fun-

- nel shaped insulating means at the surface of the mercury cathode having its wider-open end facing said anode and means for creating a new cathode spot at the beginning of each conducting portion of the cycle of current within the funnel shaped portion of said insulating means, said insulating means having a portion protecting said cathode spot creating means from the direct arc between said anode and cathode.
10. 5. An electric discharge device comprising a casing having a gaseous atmosphere at several atmospheres pressure, an anode and a liquid cathode therein, tubular insulating means forming a restricted column extending above the surface of the liquid cathode and means for creating a cathode spot at the surface of the liquid cathode at the base of said restricted column.
15. 6. An electric discharge device comprising a casing having a gaseous atmosphere at several atmospheres pressure, an anode and a liquid cathode therein, tubular insulating means forming a restricted column extending above the surface of the liquid cathode and means for creating a cathode spot at the surface of the liquid cathode at the base of said restricted column, said last mentioned means being protected from the direct arc between said anode and cathode.
20. 7. A vacuum-tight container enclosing an anode and a vaporizable cathode, an unobstructed straight path from said cathode to said anode, means to intermittently excite said cathode, guide walls near the surface of said cathode for directing the vapor produced by said excitation toward said anode.
25. 8. A vacuum-tight container enclosing an anode and a vaporizable cathode, means to intermittently excite said cathode, guide walls near

the surface of said cathode for directing the vapor produced by said excitation toward said anode, a gaseous atmosphere of a pressure greater than an atmosphere within said container.

9. A vacuum-tight container enclosing an anode and a vaporizable cathode, means to intermittently excite said cathode, guide walls near the surface of said cathode for directing the vapor produced by said excitation toward said anode, a shield covering the surface of said cathode outside the path of said vapor.

10. A vacuum-tight container enclosing an anode and a vaporizable cathode, means to intermittently excite said cathode, guide walls near the surface of said cathode for directing the vapor produced by said excitation toward said anode, a shield covering the surface of said cathode outside the path of said vapor, a gaseous atmosphere of a pressure greater than an atmosphere within said container.

11. A vacuum-tight container enclosing an anode and a vaporizable cathode, an igniter electrode acting to intermittently excite a spot on said cathode, guide walls near the surface of said cathode for directing the vapor produced by said excitation toward said anode, and means tending to produce flow of pulsating current between said anode and cathode.

12. A vacuum-tight container enclosing an anode and a vaporizable cathode, an igniter electrode acting to intermittently excite a spot on said cathode, guide walls near the surface of said cathode for directing the vapor produced by said excitation toward said anode, and a gaseous atmosphere of a pressure greater than one atmosphere in said container.
